UNITED STATES PATENT OFFICE.

CHRISTIAN A. BUSCHAM, OF IRVINGTON, NEW JERSEY, ASSIGNOR TO C. A. BUSCHAM MFG. CO., OF IRVINGTON, NEW JERSEY.

VANITY CASE OF WATCHCASE TYPE.

Application filed September 21, 1925. Serial No. 57,642.

This invention relates to toilet articles and has special reference to that class of toilet articles which are commonly known as "compacts," or vanity cases of watch case type.

One object of the invention is to improve the general construction of devices of this character.

A second object of the invention is to provide an improved compact having the parts nested with respect to each other, one container being provided with a lid or cover and forming a lid or cover for a second container.

15 A third object of the invention is to provide a compact of the above character wherein each container will be provided with its own mirror, the latter being exposed only when the particular container is opened.

20 With the above and other objects in view as will be hereinafter apparent, the invention consists in general of certain novel details of construction and combinations of parts hereinafter fully described, illustrated 25 in the accompanying drawings and specifically claimed.

In the accompanying drawings like characters of reference indicate like parts in the several views, and:

30 Figure 1 is a plan view of the compact showing the same closed.

Figure 2 is a front view of the same showing the rouge container open.

Figure 3 is a front view showing the powder container open.

Figure 4 is an enlarged section on the line 4-4 of Figure 1.

Figure 5 is a view in top plan showing the two containers separated in order to disclose the hinge construction.

Figure 6 is a bottom plan partly broken away to show the hinge construction.

In the present embodiment of the invention the compact is shown as provided with 45 a main bottom member 10 which is preferably made of thin sheet metal pressed into substantially segmento spherical form and on the edge of this member is carried a ring 11 the edge of which is pressed or spun over the edge of the bottom 10. This ring is provided with a depending inner cylindrical flange 13 the lower edge of which engages the bottom 10, thus forming a shallow concave bottomed cell or container wherein 50 may be placed a cake of face powder.

In order to form a lid or cover for this part of the device there is provided an outer ring 14 having an outer depending flange 15 and an inner depending flange 16 spaced from the flange 15. Fitted within the outer 60 flange 15 is a ring 17 having at its bottom an inwardly projecting flange 18 whereon rests a mirror 19 backed by a disk 20 of cardboard or the like. The mirror and cardboard are thus gripped between the 65 flanges 16 and 18 and form the bottom of a second shallow container wherein may be placed a cake of rouge.

To cover the rouge container there is provided a top 21 having a rebent edge 22 from which depends a flange 23, the edge and flange fitting closely in the ring 14 and its inner flange 16. Fitted in the flange 23 is a bezel 24 which serves to hold a mirror 25 in position.

To hinge the parts together, the rings 11 and 15 each have a slot 26 formed therein and the ring 11 is provided with a tubular projection 27 radially alined with its slot and passing through the slot 26 of the ring 11. Similarly, the top 21 is provided with a tubular projection 28 which passes through the slot of the ring 14. Pins 29 serve to hold these tubular projections in position.

In assembling the pins are positioned as 85 shown in full lines in Figure 5 and the projecting end of the top pin hooked into the slot of the ring 14. The pin is then pushed to the position shown in dotted lines in that figure. Next the rings 14 and 11 are similarly secured. Finally the bottom is placed in 90 position and the ring 11 pressed or sprung thereon.

Thumb nail slots 30 are of course provided to enable the cover to be opened.

There has thus been provided a simple and efficient device of the kind described and for the purpose specified.

It is obvious that minor changes may be made in the form and construction of the 100 invention without departing from the material spirit thereof. It is not, therefore, desired to confine the invention to the exact form herein shown and described, but it is desired to include all such as properly come 105 within the scope claimed.

Having thus described the invention, what I claim as new, is:

1. In a compact, an outer case, a ring having an annular portion forming a partial 110

- cover for the outer case and having a short cylindrical portion forming an inner case and having a bottom forming the remainder of the cover for the outer case, a hinge connection between the outer periphery of the ring and the outer case, a cover for the inner case nesting within the same, and a hinge connection between said cover and the inner periphery of the ring.
5. In a compact, an outer case, a ring having an annular portion forming a partial cover for the outer case and having a short cylindrical portion forming an inner case and having a mirror constituting its bottom and forming the remainder of the cover for the outer case, a hinge connection between the outer periphery of the ring and the outer case, a cover for the inner case nesting within the same, and a hinge connection between said cover and the inner periphery of the ring.
10. 2. In a compact, an outer case, a ring having an annular portion forming a partial cover for the outer case and having a short cylindrical portion forming an inner case and having a mirror constituting its bottom and forming the remainder of the cover for the outer case, a hinge connection between the outer periphery of the ring and the outer case, a cover for the inner case nesting within the same, and a hinge connection between said cover and the inner periphery of the ring.
15. 3. In a compact, and outer case, a ring having an annular portion forming a partial cover for the outer case and having a short cylindrical portion forming an inner case and having a mirror constituting its bottom and forming the remainder of the cover for the outer case, a hinge connection between the outer periphery of the ring and the outer case, a cover for the inner case nesting within the same, and a hinge connection between said cover and the inner periphery of the ring, said inner case being nested within the outer case.
20. 4. In a compact, an outer case having a peripheral portion overhanging its body, an inner case forming a cover for the outer case and hinged to the inner edge of the overhanging portion, said cover having a central cosmetic receiving portion provided with a peripherally extending flange ring at its upper edge and a cover hinged to said inner case, said inner case being nested within said outer case, and mirrors supported by the lower side of the inner case and 45 its cover respectively.
25. 5. In a compact, an outer case, an inner case comprising a ring having an inner edge and an outer edge concentric with the inner edge, said outer edge being hinged to 50 the outer case and carrying a mirror forming the bottom of the inner case, said ring and mirror forming a cover for the outer case, and a cover for the inner case hinged to said ring, and a second mirror supported 55 within said inner case cover.
30. 6. In a compact, an outer case, an inner case comprising a ring having an inner edge and an outer edge concentric with the inner edge, said outer edge being hinged to the 60 outer case and carrying a mirror forming the bottom of the inner case, said ring and mirror forming a cover for the outer case, and a cover for the inner case hinged to said ring, said inner case being nested with said 65 outer case, and a second mirror supported within said inner case cover.
35. 4. In a compact, an outer case having a

In testimony whereof I affix my signature.

CHRISTIAN A. BUSCHAM.
